DESIGN FOR A SOAP HOLDER

Theola Benoto, St. Louis, Mo.

Application March 17, 1944, Serial No. 112,940

Term of patent 7 years

(Cl. D4—3)

To all whom it may concern:

Be it known that I, Theola Benoto, a citizen of the United States and a resident of the city of St. Louis and State of Missouri, have invented a new, original, and ornamental Design for a Soap Holder, of which the following is a specification, reference being had to the accompanying drawing, forming part thereof.

Figs. 1, 2, 3 and 4 are, respectively, a perspective view, a top plan view, an end elevational view and a bottom plan view of a soap holder, showing my new design.

I claim:

The ornamental design for a soap holder, as shown.

THEOLA BENOTO.
